UNITED STATES PATENT OFFICE

GEORGE C. FAIRBAIRN, OF PORT ARTHUR, TEXAS, ASSIGNOR TO THE TEXAS COMPANY,
OF NEW YORK, N. Y., A CORPORATION OF DELAWARE

VISCOSIMETER

Application filed January 15, 1930. Serial No. 420,863.

This invention relates to viscosimeters and more particularly to viscosimeter apparatus by means of which the viscosity of liquids, especially oils, may be rapidly and accurately 5 determined.

Among the novel features of the invention the following may be briefly set forth:

The provision of means whereby a bath adapted to contain a plurality of viscosimeter 10 tubes may be uniformly and constantly maintained at any desired temperature.

The provision of thermo-regulator mechanism possessing a very high degree of sensitivity adapted to regulate the temperature 15 of the bath liquid.

The provision of mechanical stoppers for the viscosimeter discharge tubes and automatic means whereby these individual stoppers may be released while simultaneously 20 starting individual second counters or other suitable timing devices adapted to determine accurately the time of efflux of a given quantity of liquid from the viscosimeter tubes.

These and other novel features of the invention will be more clearly understood from the following detailed description which has reference to the accompanying drawings illustrating diagrammatically and in some detail 25 a preferred embodiment of the apparatus of the invention in which:

Figure 1 is a diagrammatic illustration, partially in section, of the viscosimeter apparatus and the several electric circuits.

Figure 2 is a plan view of the viscosimeter 35 bath container showing disposition of heating element, stirring paddles, viscosity tubes, etc. within the bath.

Figure 3 is a view in elevation, partly in section, of the thermo-regulator mechanism.

Figure 4 is a partial plan view of the 40 thermo-regulator mechanism shown in Figure 3.

Figure 5 is an enlarged plan view of the 45 rotating contact disc of the thermo-regulator mechanism shown in Figures 3 and 4.

Figure 6 is a view in sectional elevation of a viscosimeter receptacle discharge tube and stopper mechanism.

Figure 7 is a view in elevation, partly in 50 section, of an electro-magnetic switch for si-

multaneously starting a second counter and releasing a viscosimeter tube stopper mechanism.

Figure 8 is a view in elevation of the contacting mechanism of the electro-magnetic 55 switch shown in Fig. 7.

In Figures 1 and 2 a rectangular chamber 1 or bath container having a cover plate 1a fabricated from steel or some other suitable material, adapted to contain a heating fluid 60 is appropriately heat insulated on the sides and bottom by an asbestos material 2 which is held in place by a metal covering or jacket 3. Sheet asbestos may preferably be used to insulate the bottom of the chamber instead of 65 powdered material in order to provide a more solid and rigid base.

A plurality of viscosimeter receptacles or tubes 4 and discharge tubes 61 such as are used in conventional viscosity testing machines extend through the bath from top to bottom in a manner similar to that employed in the conventional single tube viscosity testing machine. The joints between the discharge tubes 61 and the bottom of the bath 75 are made proof against leaks so as to prevent the escape of the heating fluid from within the bath.

An electrical heating coil 5 preferably composed of two coil elements 5a and 5b of ni-chrome ribbon or other suitable resistance wire, non-inductively wound about a tube or supporting means 6 and having terminals 7a and 7b at one end and a single terminal 8 at the opposite end, all of which are connected 80 with an electrical power supply transmitting system 46 through a relay switch 9 which is controlled by a thermo-regulator mechanism or circuit controller 10, as will be fully described later in the detailed discussion of Figures 3, 4, and 5, is placed within the bath 1 preferably extending lengthwise there-through about mid-way between the sides and so that it is completely submerged in the 85 bath liquid at all times.

The supporting means 6 is preferably a section of copper tubing having brass flanges 11 threaded on at each end, which are in turn fastened to the end plates of the bath by flange bolts 12. Gaskets are inserted between 90 95 100

the flanges and the metal end plates of the bath to make the joints leak proof. Holes are drilled and tapped in the ends of the bath 1 at points corresponding to the centres of the flanges 11 in order to accommodate an inlet pipe 12 of

tached to the lower end of the helix, and a worm 32 adapted to mesh with the worm gear 28 which is rigidly mounted on the upper end of the hollow shaft 27 to thereby pro-

9 such as may be readily obtained on the market and of which the principles and operation are generally understood.

The relay coils 9a of which 9 have two terminals X and Y as shown in Fig. 1, the terminal X is directly connected by a wire 47 to a current conductor 46a of an electrical power supply transmitting system 46, leading from a source of supply not shown, while the terminal Y is connected by a wire 53 to the terminal 44 of the circuit controller brush 42. The terminal 33a at the pivoted end of arm 31 is connected by a wire 54 to the conductor 46b of the transmission system or circuit 46. Consequently when the tip 35 of arm 31 makes contact with the rotating disc 36 an electrical circuit is completed through the relay coils 9a causing them to be energized.

20 The relay coils 9a control by mechanical means the making and breaking of contact between the contact points N—M and N—O of the relay switch. That is when the relay coils 9a are energized, contact between N and M is established by the rocking of a mercury contactor 9b while contact between N and O is broken and conversely when the relay coils 9a are deenergized contact between contact points N and O is established while contact 25 between contact points N and M is broken. The operation of the switch is such that it has no neutral position.

The relay switch 9 may be connected so that the contact point N and the contact point M 30 on one side of the switch form a means for either closing or opening the circuit, which includes the heating coil 5, by rocking the contactor 9b while the contact point N and contact point O on the other side of the switch 35 form a means for either closing or opening a separate circuit, which includes the solenoid valve 14, by rocking the contactor 9b.

The heating coil circuit preferably comprises a branch current conductor 49 having a hand switch 49a leading from the main current conductor 46b and connecting directly to the terminals 7a and 7b of the dual heating coil 5, a branch current conductor 48 leading from the main current conductor 46a and connecting directly to the contact point N 45 of the relay switch 9, and another branch conductor 50 connecting the contact point M of the relay switch 9 with the single terminal 8 at the other end of the heating coil 5.

50 The solenoid valve circuit comprises a branch current conductor 51 leading from the main current conductor 46b and connecting directly with a terminal 14a of the solenoid valve 14, the wire 48 previously described and the branch current conductor 52 connecting the contact point O of relay switch 9 with another terminal 14b of the solenoid valve 14.

When the bath temperature falls below a predetermined point the thermostat element

26 causes the arm 31 to make contact with the rotating disc 35 thereby completing a circuit through and energizing the relay coils 9a of relay switch 9 which operates to establish a contact between the points N and M of the relay switch causing an electrical current to flow through the heating coil elements having just previously broken the contact between the points N and O of the solenoid valve circuit side of the relay switch, which caused the valve 14 to close and thereby stop the flow of water or cooling medium through the cooling tube 6. On the other hand it is to be seen that when the temperature of the bath liquid exceeds a certain predetermined point the thermostat 26 will cause the arm 31 to break contact with the rotating disc 35 thereby opening the relay coil circuit, deenergizing the relay coils which causes the position of the mercury contactor to be reversed 80 so that the heating element circuit is opened stopping the flow of electrical current therethrough while the solenoid valve 14 is opened permitting cooling fluid to flow through tube 6.

85 While the elements of the heating coil 5 are shown connected in parallel, it may be preferable in some cases to substitute a three way switch for the one way switch 49a whereby the elements may be connected either singly or in parallel or in series to thereby vary the amount of heat added to the bath liquid which serves to permit a variance in the operating temperature of the viscosimeter over a wide temperature range and also 90 makes provision for considerable changes in atmospheric conditions surrounding the machine.

95 In Fig. 6 number 4 refers to a conventional viscosimeter receptacle or tube having a cylindrical chamber 55 the upper portion of which is of enlarged diameter to form a cuplike container 56 while the lower portion 57 is of reduced diameter, having a restricted passage or orifice 58 therethrough, and is 100 threaded so as to be screwed into a discharge tube 61, the joint between the tube 4 and the discharge tube 61 being made leak proof by means of a suitable gasket 60.

105 The discharge tube 61 is similar to the conventional type of discharge tube, available on the market, having a non-restricted passage therethrough, a circular shoulder 63 intermediate the ends thereof and its upper end having internal threads to accommodate the reduced threaded end 57 of the receptacle 55 while its lower portion is threaded externally to accommodate a securing nut 64. The discharge tube 61 having the receptacle 55 attached to its upper end extends 110 through a hole provided in the bottom of the bath 1, a suitable gasket 65 being inserted between the inner surface of the bottom of the bath and the shoulder 63 of the discharge tube, to render the joint leak-proof. et 66 which is adapted to slip over the threaded portion of the tube protruding beyond the bottom of the bath container is preferably held in position by the nut 64.

5 Referring to Figures 1, 7 and 8 the electro-magnetic switch mechanism, which may be mounted on a suitable panel 78 attached to a frame or legs supporting the viscosimeter bath, comprises a conventional electro-magnetic 10 net or relay 79 supported in an appropriate metal frame 80 which is rigidly attached to two vertical members 81a and 81b, preferably made of a phenolic condensation product or another non-conductive material, which are 15 rigidly mounted on the panel 78 having suitable spacers 82a and 82b preferably made of brass, set between the ends of the members 81a and 81b and the panel 78.

Attached to the vertical members 81a and 20 81b are spring contact strips 84a and 84b, each having a binding post to which may also be fastened branch conductors 85a and 85b. A slidable member 86 is provided, preferably of a phenolic condensation product or the 25 like which has a contact strip 87 attached thereto. The contact strip 87 serves to establish contact between the spring strips 84a and 84b terminating the branch conductors 85a and 85b when it is moved upwardly and 30 makes joint contact therewith as the attaching slidable member 86 is moved upwardly. The spring strips press against the contact strip 87 to insure positive contact between the spring strips and the contact strip 87. 35 One end of the lever 88 projects through an opening 89 provided in the slidable member, thus making it available for manual actuation at times, while the other end which is threaded to adjustably accommodate a 40 counter-weight 91, is closely attached to the frame by a pin 90.

A depending arm 67 of the bracket 66 supports an electro-magnet 68 while a depending arm 69 supports a stopper arm 70 rockably 45 attached thereto by a pin 71. One end of a tension spring 72 is attached to the stopper arm 70 preferably near its midpoint while the other end is suitably attached at a point 73 on horizontal extension of the arm 69 so 50 as to hold the stopper arm 70 back in an open position when the stopper is released. A depending catch 74, pivotally swung from the bracket 66 by a pin 75, is adapted to hold the surface of a stopper element 76, which is a separable part of the stopper arm 70, tightly 55 against the protruding end of the discharge tube 61, in which position of the stopper arm spring 72 is somewhat extended. The stopper element 76 preferably consists of a disc shaped piece of cork appropriately secured in the stopper arm 70 which may be replaced 60

When the electro-magnet 68 is energized the free end of the depending catch 75 is attracted by the magnet 68 and it is caused 65 whenever necessary.

to swing towards the magnet thus releasing the stopper arm 70 which is immediately jerked back to the limit of its open position by the spring 72 as is shown in the drawings.

The electro-magnet 68 is preferably connected in series with a second counter 77, which is merely indicated in Fig. 1 and which will not be described as this is conventional equipment and may be readily obtained in the market, and suitable electro-magnetic 75 switch mechanism particularly adapted to start the counter simultaneously as the stopper is released which will now be described in detail.

The lever 88, which is preferably of steel, 80 is normally raised by the electro-magnet 79 and lifts with it the slidable member 86, thereby moving the strip 87 into contact with the spring strips 84a and 84b thus closing the circuit. Due to the pressure of the spring strips 84a and 84b upon the contact strip 87 and also the counterbalancing effect of the counterweight 91 the switch will remain in a closed position without the electro-magnet 79 being maintained in an energized state. 85 This circuit is normally opened by manually lowering the lever 88.

The circuit which transmits power to energize the electro-magnet 79 is shown extensively in Fig. 1. Number 98 indicates a 90 transformer adapted to step a relatively high voltage down to a relatively low voltage to thus furnish a relatively low voltage to a series circuit which comprises the relay 68 of the discharge tube stopper release mechanism, relay 79 of the electro-magnet switch mechanism and the actuating mechanism of the second counter 77. Terminal B on the secondary side of transformer 98 is connected by a wire 97 to terminal B' of the second counter 77 while the other secondary 100 terminal A is connected by a wire 96 to one terminal of the relay 68 the other terminal of which is connected by a wire 95 to one side 105 of a push button switch 92. The other side 110 of the switch 92 is connected by a wire 94a to one terminal of the relay 79 the other terminal of which is connected by a wire 94b to the terminal A' of the second counter 77. Terminal A of transformer 98 is also connected by the wire 85b to the spring contact strip 84b while contact spring strip 84a is connected by the wire 85a to terminal A' of the second counter 77 thus forming an individual or separate circuit for the second counter 77 which is closed or opened depending upon the position of the switch lever 88.

Accordingly when the push button 92 is closed the circuit is closed, simultaneously energizing relays 68 and 79 with the result that the second counter 77 is started at the exact instant that stopper 70, upon being released by catch 74, is jerked open by the spring 72 thus permitting the liquid within the receptacle or tube 4 to discharge through 115 120 125 130

the discharge tube 61 into a receiving flask 100.

Once the relay 79 has closed the contacts 84a and 84b the second counter continues to 5 operate even after the push button switch 92 is released and normally it may be stopped only by manually lowering the switch lever 88 which is preferably done as soon as the liquid level in the receiving flask 100 reaches 10 a graduation mark 101.

Thus by the perfect timing of the mechanical operation of the stopper release mechanism simultaneously with that of the second counter starting switch mechanism the simultaneous starting of the discharge of the fluid to be tested and the starting of the second counter is accomplished, which insures that the determination or reading of the viscosity test may be made to a degree of precision 20 much greater than has hitherto been possible with the conventional viscosimeter machine where manual removal simultaneously of the stopper and starting of the timing device is attempted.

25 While the use of alternating current has been mentioned in describing the electrical apparatus, the apparatus is readily adaptable to the employment of direct current.

Obviously many modifications and variations of the invention, as herein set forth may be made without departing from the spirit and scope thereof and therefore only such limitations should be imposed as are indicated in the appended claims.

35 I claim:

1. A viscosimeter bath comprising a receptacle for holding the bath fluid, a centrally disposed horizontal tube extending through the receptacle, a heating element coiled 40 around a portion of said tube within the receptacle and connected to a source of electrical energy, means for making and breaking the electrical circuit through said coil in response to changes in the temperature of the 45 bath fluid, and means for passing a fluid cooling medium through the tube supporting the heating element to absorb excess heat from the heating coil when the temperature of the bath fluid exceeds a predetermined maximum.

50 2. A viscosimeter bath comprising a receptacle for holding the bath fluid, a centrally disposed horizontal tube extending through the receptacle, a heating element 55 coiled around a portion of said tube within the receptacle and connected to a source of electrical energy, means for making and breaking the electrical circuit through said coil, a valved tubular member connected at 60 one end to a source of a fluid cooling medium and at its other end to the tube extending through the receptacle, and means responsive to fluctuations in the temperature of the bath 65 for alternately breaking and making the electrical circuit through the heating element and

for opening and closing the valve in the tube member to control the passage of the cooling fluid through the tube around which the heating element is coiled.

3. A viscosimeter bath comprising a receptacle for holding the bath fluid, a heating element disposed in the receptacle, means for making and breaking the electrical circuit through said element comprising, a switch 70 for controlling the energization of the heating element, a control circuit for said switch, including a coil adapted to actuate said switch, a continuously rotating contact member and a movable arm in series with said coil, said arm having at one end a contact point adapted to form a non-sticking contact 75 with the rotating contact surface, and means responsive to changes in temperature in the bath fluid for moving the arm into contact and away from the rotating contact surface 80 to make and break the circuit through said coil.

In witness whereof I have hereunto set my hand this 11th day of December, 1929.
